(57) **CLAIM**

The ornamental design for a game board, as shown and described.

DESCRIPTION

FIG. 1 is a top-front perspective view of a game board;

FIG. 2 is a front view of the game board;

FIG. 3 is a back view of the game board;

FIG. 4 is a right side view of the game board;

FIG. 5 is a left side view of the game board;

FIG. 6 is a top view of the game board; and,

FIG. 7 is a bottom view of the game board.

The broken lines in the drawings are for illustrative purposes only and form no part of the claimed design.

1 Claim, 6 Drawing Sheets
